UNITED STATES PATENT OFFICE.

JOHANN AUGUST FRIEDRICH CARL SEUMENICHT, OF LÄGERDORF,
GERMANY.

SHAFT-FURNACE FOR BURNING CEMENT, &c.

SPECIFICATION forming part of Letters Patent No. 699,852, dated May 13, 1902.

Application filed July 27, 1900. Serial No. 25,021. (No model.)

To all whom it may concern:

Be it known that I, JOHANN AUGUST FRIEDRICH CARL SEUMENICHT, a subject of the Duke of Brunswick, residing at Lägerdorf, in the 5 Kingdom of Prussia, German Empire, have invented certain new and useful Improvements in Shaft-Furnaces for Burning Cement and the Like, (for which I have applied for a patent in Germany, dated July 4, 1899,) of 10 which the following is a specification.

The present invention relates to that class of shaft-furnaces for burning cement and the like in which the raw material is dried in a 15 drying-chamber heated by the waste heat of the furnace.

In this new furnace a preliminary-heating chamber is provided, in which the raw material after having been dried in the drying-chamber is heated before being introduced 20 into the combustion or smelting chamber.

The invention consists, essentially, in the arrangement at the height of the feed-opening in the preliminary-heating chamber of a drying-chamber inside another chamber, 25 which is situated above the main combustion or smelting chamber and beside the preliminary-heating chamber, so that the walls of the drying-chamber are protected as far as possible from the action of the external air.

30 In the accompanying drawing a vertical section of a furnace constructed in accordance with this invention is represented.

The shaft-furnace consists of seven compartments—viz., A, the combustion-chamber; B, the preliminary-heating chamber; F, an intermediate chamber connecting through chamber E the preliminary-heating chamber B with T, the drying-chamber, and D the flue connected with chamber T through chamber G.

40 The combustion or smelting chamber A is connected by the channel H to the preliminary-heating chamber B. In a line with the preliminary-heating chamber, but separated 45 therefrom by the arch or partition C, the flue D of the furnace is situated. At the top of the heating-chamber an opening is provided in the side W, so that the gases issuing from the preliminary-heating chamber can pass 50 into the chamber E, thence downwardly into chamber F underneath the drying-chamber. Openings of a suitable size connect chamber F with the drying-chamber T, which contains the fresh material to be dried on carriages or

other suitable supports. In the top of this 55 drying-chamber T there are a number of openings through which the gases escape into the chamber G and from thence pass into the flue D above the arch or partition C. The drying-chamber is situated at the height of 60 the charge-opening of the furnace in an otherwise dead space, and as it is arranged beside the preliminary-heating chamber, the gases being drawn down through the chamber E into chamber F, it is exposed to the hot gases 65 issuing from the preliminary-heating chamber. The technical advantage of this arrangement is that the gases issuing from the combustion or smelting chamber are not conducted directly into the drying-chamber, as in existing 70 constructions, whereby, in the first place, the raw material is exposed to too excessive heat, and, in the second place, the gases escaping into the flue still possess such a high temperature that an economical combustion of the fuel is quite out of question, 75 but after leaving the combustion-chamber first pass into the preliminary-heating chamber, where they still burn, and then through intermediate protecting-chambers into the 80 drying-chamber at a considerably lower temperature. With this arrangement the carriages or other supports containing the raw material are not liable to being burned, and the gases of combustion are utilized as far as 85 possible before escaping into the flue.

What I claim, and desire to secure by Letters Patent of the United States, is—

In combination in a furnace, a drying-chamber, heating and protecting chambers above 90 and below said drying-chamber and opening thereto, a combustion-chamber, a preliminary-heating chamber into which the hot gases from the combustion-chamber pass, and a heating and protecting chamber lying back 95 of the drying-chamber and connecting the preliminary-heating chamber with the chamber below the drying-chamber, the gases passing therethrough in a downward direction, substantially as set forth.

100 In testimony whereof I have hereunto set my hand in the presence of two witnesses.

JOHANN AUGUST FRIEDRICH
CARL SEUMENICHT.
